CLAIM

The ornamental design for a tool bit container, as shown and described.

DESCRIPTION

FIG. 1 is a perspective view of a tool bit container showing our new design.

FIG. 2 is a front view of the tool bit container of FIG. 1.

FIG. 3 is a rear view of the tool bit container of FIG. 1.

FIG. 4 is a left view of the tool bit container of FIG. 1.

FIG. 5 is a right view of the tool bit container of FIG. 1.

FIG. 6 is a top view of the tool bit container of FIG. 1; and,

FIG. 7 is a bottom view of the tool bit container of FIG. 1. The portions in broken lines form no part of the claimed design.

1 Claim, 6 Drawing Sheets
